UNITED STATES PATENT OFFICE.

LEONARD WILSON, OF PITTSFIELD, MASSACHUSETTS, ASSIGNOR TO
STANLEY ELECTRIC MANUFACTURING COMPANY, OF PITTSFIELD,
MASSACHUSETTS, A CORPORATION OF NEW JERSEY.

ELECTRIC RHEOSTAT.

SPECIFICATION forming part of Letters Patent No. 741,206, dated October 13, 1903.

Application filed April 6, 1903. Serial No. 151,230. (No model.)

To all whom it may concern:

Be it known that I, LEONARD WILSON, a subject of the King of England, and a resident of Pittsfield, Massachusetts, have invented certain new and useful Improvements in Electric Rheostats, of which the following is a specification.

The object of my invention is to provide a rheostat which shall allow the current passing through any electrical apparatus to be varied gradually from zero to maximum, which shall be simple and cheap in construction, and which shall be economical in operation.

15 My invention consists, broadly, in cutting out part of the resistance in series with a circuit and simultaneously cutting in a shunt resistance, thereby effecting a saving in resistance material, while giving a very even 20 adjustment of circuit strength. My invention consists also in certain details of arrangement adapted to secure this result and described in the following specification.

25 The drawing shows diagrammatically an arrangement embodying my invention.

In the drawing I have shown my invention applied to the field of a separately-excited generator; but it will be understood that my invention is equally applicable to other electrical apparatus in which it is desirable that the current be gradually and economically varied between wide limits.

30 Referring to the drawing, A represents the armature, and B the field, of a separately-excited generator.

35 C C' are the exciter bus-bars.

D and E are resistances connected at suitable intervals to contact-buttons d' d², &c., and to e' e², &c., respectively.

40 f' f², &c., are extra contact-buttons connected to e' e², &c.

F is a contact-strip connected to f'.

F' is a contact-strip connected to d¹⁸.

45 G is a rotary arm pivoted at H, connected to one end of field B' and adapted to make contact with the contact-buttons and with the contact-strips F and F'.

I is a switch for opening the field and rheostat circuit.

J is a stop for rheostat-arm G.

50 The operation will be obvious from the drawing and the following explanation. Assume, for example, that the voltage between exciter bus-bars C C' is one hundred and that the values of the resistance of field B, of 55 resistance D, and of resistance E are twenty ohms each. Now starting with the arm G in the position shown, field B is short-circuited, and no current flows through it. As arm G

is moved along contacts d' d², &c., and in contact with strip F the resistance-shunting field B is gradually increased and more and more current flows through field B until when arm G reaches d¹⁸ all of resistance D is in shunt or parallel circuit with field B and all of 60 resistance E is in series with the parallel circuit. The resistance of the circuit between bus-bars C C' is now thirty ohms. The current is therefore three and one-third amperes, one-half of which, or one and two-thirds am- 65 peres, flows through field B. As arm G moves from d¹⁸ to f' and from F to F' no change in resistance takes place. Now as arm G is moved along contacts f' f², &c., part of resistance E

70 is gradually cut out until when arm G is in 75 contact with f⁶ half of E is cut out. The resistance of the circuit between bus-bars C C' is now twenty ohms. The current is therefore five amperes, one-half of which, or two and one-half amperes, flows through field B. 80 Now as arm G passes from f⁶ to e' the connection with contact-strip F', and consequently with resistance D, is broken, while all of resistance E is placed in series with field B.

85 The resistance between bus-bars C C' is now forty ohms. The current is therefore two and one-half amperes, all of which passes through field B, since field B is no longer shunted. Thus it is seen that the current through field B is not changed by moving 90

arm G from f⁶ to e'. It will of course be understood that the step from f⁶ to e' may be so arranged as to produce a small change in the current passing through field B proportion- 95

ately to the other steps. This could be accomplished by so arranging the contacts in relation to resistance E that a little less than half of resistance E would be cut out when arm G

is in contact with f^6 . This would be preferable in practice; but for the purposes of this explanation the simpler arrangement is selected, the slight change suggested above being one that will be obvious to those skilled in the art. Now as arm G is moved along $e^1 e^2$, &c., resistance E is gradually cut out until when arm G is in contact with e^{11} field B is connected directly across the exciter bus-bars. The current through field B is now five amperes, the maximum value.

It will be obvious that it is not necessary that resistances D and E be equal to each other or to the resistance of B, but that the relative values of the resistances and the number of contacts for each resistance may be varied to suit different conditions.

I do not desire to limit myself to the particular construction and arrangement of parts herein shown, since changes therein which do not depart from the spirit of my invention will be obvious to those skilled in the art.

Having thus fully described my invention, what I claim, and desire to protect by Letters Patent, is—

1. In an electric rheostat, a series of contacts, resistances connected to said contacts, contact-strips paralleling parts of said series, each strip being connected to one of said contacts, and a movable arm adapted to engage said contacts and said contact-strips.

2. In an electric rheostat, two sets of resistances, a set of contacts connected to points on the first set of resistances, a second set of contacts connected to points on the second set of resistances, a third set of contacts connected to points on part of the second set of resistances, a contact-strip paralleling the first-named set of contacts and connected to one contact of the third-named set, a contact-strip paralleling the third-named set of contacts and connected to one contact of the first-named set, and a movable arm adapted to engage said contacts and said contact-strips.

3. In an electric rheostat, a circular row of contacts, resistances connected to said contacts, contact-strips concentric with said circular row and extending through parts of the arc of said circular row, each of said contact-strips being connected to one of said contacts, and a rotatable arm adapted to engage said contacts and said contact-strips.

4. In combination, an electric circuit, two sets of resistances, a set of contacts connected to said resistances, and a switch-arm coöperating with said contacts, said switch-arm being adapted to connect step by step one of said sets of resistances in series with said circuit, then to cut out part of said set of resistances and to connect the second set of resistances in shunt to said circuit, then to cut in again step by step the whole of the first set of resistances in series with said circuit, and

then to short-circuit step by step the said second set of resistances.

5. In combination, an electric circuit, two sets of variable resistances, and a switch adapted to place one of said sets in series with said circuit and then to place part of the first set in series and the second set in shunt with said circuit.

6. In combination, constant - potential mains, a resistance connected at one end to one of said mains and at the other end to a contact-strip, a second resistance connected at one end to the second main, and at the other end to a second contact-strip, contacts connected to points on said resistances, a movable arm adapted to engage said contacts and said contact-strips, and an electric circuit connected at one end to one of the said mains and at the other end to said movable arm.

7. In combination, constant - potential mains, two variable resistances, an electric circuit connected at one end to one of said mains, a movable switch-arm connected to the other end of said circuit and adapted to connect one of said variable resistances in series with said circuit, then to connect part of said resistance in series and the second of said variable resistances in shunt with said circuit, and then to connect the whole of the first resistance in series and the second resistance in shunt with said circuit.

8. In combination, an electric circuit, variable resistances connected to a series of contacts, and a movable switch-arm adapted to connect a part of said variable resistances in series with said circuit and then to connect a part of said resistances in series and a part in shunt with said circuit.

9. In an electric rheostat, two variable resistances, and a movable arm adapted to connect a variable portion of one resistance in series with the second resistance, then to connect the first resistance in series with the variable portion of a second resistance, then to cut out the first resistance, and then to cut out a variable portion of the second resistance.

10. In combination, an electric circuit, a rheostat therefor, and a switch adapted to place part of said rheostat in series with said circuit and then to simultaneously cut out part of said series resistance and connect part of said rheostat in shunt with said circuit.

11. In combination, an electric circuit, series and shunt resistances therefor, and a switch adapted to cut out part of said series resistance when cutting in said shunt resistance.

Signed at Pittsfield, Massachusetts, this 31st day of March, 1903.

LEONARD WILSON.
